UNITED STATES PATENT OFFICE.

HARRY S. HART, OF CHICAGO, ILLINOIS, ASSIGNOR TO WOLFF TRUCK FRAME COMPANY, OF CHICAGO, ILLINOIS, A CORPORATION OF MAINE.

RAILWAY CAR-TRUCK.

No. 895,559.

Specification of Letters Patent.

Patented Aug. 11, 1908.

Application filed December 17, 1906. Serial No. 348,267.

To all whom it may concern:

Be it known that I, HARRY S. HART, a citizen of the United States, residing at Chicago, in the county of Cook and State of Illinois, have invented certain new and useful Improvements in Railway-Car Trucks, of which the following is a specification.

My invention relates to railway car trucks; and has for its object to provide an improved truck in which provision is made for the ready and quick removal of the bolster.

With this and other objects in view which will hereinafter appear, my invention consists in the combinations and details set forth and claimed.

In the accompanying drawings—Figure 1 is a side elevation of a portion of a railway truck containing my improvements. Fig. 2 is a top plan view of a part of the upper member or arch bar of the truck. Fig. 3 is a side elevation of the parts shown in Fig. 2 partly in section. Fig. 4 is a sectional plan view on the line 4 of Fig. 3. Fig. 5 is a transverse section on the line 5 of Fig. 4.

In the drawings, I have shown my invention as applied to a cast metal side frame in which the upper and lower members or arch bars and the column guides are made or cast in an integral piece. The journal boxes may also be cast integral or made separate as desired. The upper member of the side frame is provided with a removable section over the bolster, whereby when this section is removed the bolster may readily be removed from the truck. Side frames of this kind are well-known in the art and have proven highly efficient and satisfactory in service. It has been found difficult, however, to construct these cast metal side frames in such manner that the removable section will always fit in place, on account of the inequalities which are present in castings of this sort. For economical reasons, no machine work is permissible in making these devices, consequently, it often happens that in castings inequalities appear which make it necessary to drive the removable section into position with considerable force. This results in placing an initial tension upon the tension members, which is undesirable. By my invention I provide means whereby the removable section is made of less length than is ordinarily the case and I provide a means for adjustably securing this section in position,

whereby any inequalities in the casting are compensated for, and it is possible to readily and quickly place these sections in position and lock them in operative position by an adjustable securing device.

In the drawings *a* represents the upper member or arch bar of a cast metal side frame of the well-known type; *b* the lower member having inclined portions *c* connected to the upper member; *d* the tie bar secured to the journal boxes *e* to the lower member; *f* the column guides; *g* a bolster having its ends held between the column guides, and *h* the spring supporting the bolster—all in the ordinary manner.

The upper member or arch bar forming the compression member of the truss is provided with a removable section *a'* over the bolster, this member being provided for the purpose of enabling the removal of the bolster when the removable section is detached from the upper member. In the drawings I have shown this removable section at one end, as at *a'*, being reduced at its ends forming a tongue having a beveled end *a''* and similarly beveled shoulders *a'''* engaging the ends of a recess in the upper member, the ends of the recess being correspondingly beveled. Thus, it will be seen that when these ends are in engagement, the vertical movement of the removable section is prevented. At its opposite end the removable section is provided with a similar tongue *a'''* entering a recess in the opposite end of the upper member. At the end *a'''* the removable section is provided with a transverse recess, the adjacent end of the upper member being provided with a similar transverse recess, and a wedge *a''''* is mounted in these recesses, the wedge portion being screw threaded at one end for the reception of a nut *a'''''*, whereby it may be drawn into operative position, as desired.

It will be understood that the removable section is of slightly less length than the distance between the ends of the upper member, so that in case there are slight inequalities in the form of the casting, either on the upper member or on the removable section, the section may still be placed in operative position without unduly straining the parts, so as to produce undesirable tension on the members of the truss. When the wedge *a''''* is placed into position it may be driven in until the beveled end portions of the removable mem-

ber and the upper member of the truss are in engagement and the nut being tightened, the parts are securely held in place. The operation will be understood without further description.

I claim:

1. A railway car truck comprising a side frame having upper and lower truss members and columns, a bolster guided by the 10 columns, a removable section in the upper member over the bolster, and means for adjustably securing the removable section in operative position.

2. A railway car truck having side frames, 15 a bolster having its ends mounted in the side frames, and an adjustable removable section in the side frames for retaining the bolster in position.

3. A side frame for railway car trucks having a removable section in its upper member, 20 one end of the removable section and the adjacent end of the side frame member being correspondingly beveled, and means engaging the opposite end of the removable section and the adjacent end of the upper mem-

ber for forcing the beveled ends of the section and member into engagement.

4. A side frame for railway car trucks having a removable section in its upper member, 30 one end of the removable section and the adjacent end of the side frame member being correspondingly beveled, and adjustable means engaging the opposite end of the removable section and the adjacent end of the upper member for forcing the beveled ends 35 of the section and member into engagement.

5. A side frame for railway car trucks having a removable section in its upper member, 40 one end of the removable section and the adjacent end of the side frame member being correspondingly beveled, and a wedge engaging the opposite end of the removable section and the adjacent end of the upper member for forcing the beveled ends of the section and member into engagement.

HARRY S. HART.
